Des. 211,518
Patented June 25, 1968

211,518

COMBINATION INFLATABLE AND HARD SHELTER

Bernard Caminker, Tustin, La Vern A. Andrews, Fullerton, John H. Lavin, Los Alamitos, and Ronald F. Robberson, La Puente, Calif., assignors to Hughes Aircraft Company, Culver City, Calif., a corporation of Delaware

Filed Oct. 11, 1967, Ser. No. 8,951

Term of patent 14 years

(Cl. D13—1)

Fig. 2.

Fig. 3.

Fig. 5.

Fig. 4.

FIGURE 1 is a perspective view of a combination inflatable and hard shelter showing the new design;

FIGURE 2 is a front elevational view thereof, the rear elevational view being identical;

FIGURE 3 is a plan view thereof;

FIGURE 4 is a left end elevational view thereof, the right end elevational view being identical;

FIGURE 5 is a bottom view thereof.

We claim:

The ornamental design for a combination inflatable and hard shelter, substantially as shown and described.
